Primary Examiner — Keli L Hill*Assistant Examiner* — Sara S Sahneh(74) *Attorney, Agent, or Firm* — Westbridge IP LLC**(57) CLAIM**

The ornamental design for a barbecue thermometer, as shown and described.

DESCRIPTION

FIG. 1 is a front elevational view of a barbecue thermometer showing my new design;

FIG. 2 is a rear elevational view thereof;

FIG. 3 is a left side view thereof;

FIG. 4 is a right side view thereof;

(Continued)

FIG. 5 is a top plan view thereof;

FIG. 6 is a bottom plan view thereof; and,

FIG. 7 is a front perspective view thereof.

The broken lines are shown for the purpose of illustrating portions of the barbecue thermometer and forms no part of the claimed design.

1 Claim, 7 Drawing Sheets
